MASSAGING DEVICE

John H. Doenges, Clayton, Mo.

Application September 29, 1947, Serial No. 776,758

4 Claims. (Cl. 128—67)

1

This invention relates to massaging devices and in its more specific aspects is directed to a device that will simulate an ideal hand massaging action.

The object of this invention is to provide a circular massaging device whose action simulates ideal manual massaging and in which radially disposed massaging elements are provided that are caused to reciprocate toward and away from the center of said device and which act during both directions of motion of the operating massaging elements.

In the drawings:

Fig. 1 is a plan view of a device incorporating the invention;

Fig. 2 is an enlarged plan view of the device with a portion of the casing broken away to show structural detail;

Fig. 3 is a section view taken substantially along the line 3—3 of Fig. 2;

Fig. 4 is a section view taken substantially along the line 4—4 of Fig. 2;

Fig. 5 is a plan view of the supporting plate for the device shown in Figs. 2—4; and

Fig. 6 is a plan view of one of the parts shown in Figs. 2—4.

The invention is embodied in a device illustrated in the several views of the drawings in which numeral 1 designates a circular shaped casing for housing the operating parts of the device. The interior of the housing is provided with a centrally disposed longitudinally extended boss 2 to which a circular radially slotted plate 3, shown more particularly in Fig. 5, is secured by means of a screw 4. A pair of ears 5, 5 are formed on one side of the plate and a similar pair of ears are formed diametrically opposite thereto (Fig. 5). Pins 6, 6 are inserted through the ears and into extended portions 1a and 1b of the casing 1 in order to additionally support the plate 3. A roller 7 is rotatably mounted on each pin although only one such roller is illustrated.

Slidably mounted in each slot in the plate 3 is a shoe 9, in which the upper end of a pin 10 is supported, there being one pin for each shoe on plate 3. A resilient or rubber ring 8 is disposed within the circle defined by the radially inward ends of shoe members 9 for urging them and associated pins 10 toward the outer extremities of the slots in plate 3 and toward the inner wall of casing 1. A massaging assembly 11 is supported on the lower end of each pin in which each assembly comprises a suitable plate 12 to which is secured a massaging member 12' pro-

vided with a plurality of resilient fingers 13 which may be made of rubber or a suitable plastic and whose lower ends are preferably semi-spherical in shape. A fixture 14 is secured to the plate 12 that resiliently engages the rod 10' secured to the lower end of pin 10, the connection being in the form of a hinge and permitting easy removal of the massaging assembly from and pivoting about rod 10'. The rod 10' is secured to the lower end of rod 10 and at a point midway of the length of rod 10'.

Motion of the shoes 9 relative to the casing 1 in the horizontal direction, as viewed in Figs. 1—3, is produced by means of a pair of ringed straps 16 and 17. These straps move over rollers 7 and are secured to similarly constructed flat rings 18 and 19 one of said rings being shown in plan view in Fig. 6 which are disposed one above the other and about pins 10. The rings also circumscribe the shoes 9 and fit in grooves in the outer edges in the part of the shoes disposed above plate 3. Each ring has an ear formation thereon to which one end of the straps is secured, said ear formations being diametrically disposed and movable in casing extensions 1a and 1b. The ear for ring 18 in extension 1a is not shown.

Fig. 2 shows a curved cam surface formed on rings 18 and 19 which is more clearly shown in Fig. 6. The purpose of these cams is for imposing additional radial movement on the massaging elements closest to a diametrical vertical line in Fig. 2 over and above the movement that would normally be imposed thereon by the rings. The radial movement of all shoes 9 is, therefore, substantially equal.

When straps 16 and 17 are simultaneously moved in a direction away from each other, shoes 9 are radially moved in the slots in plate 3 toward the center of the plate. The radial slots in the plate, cause the massaging elements to move radially with respect to the housing. The ring 8 returns the shoes and massaging elements to the position shown in Figs. 1 and 3 following each inward radial movement by the strap. The pressure between the fingers 13 and portion of the body contacted is varied at will be the person operating the device which depends upon the extent of the downward component of the force applied to straps 16 and 17 and the resilience of ring 8. All massaging devices may be moved simultaneously toward the center of the casing 1 when straps 16 and 17 are operated simultaneously and with an action simulating the most ideal manual massage movement but with a

greatly accelerated rate because massaging action takes place during both strokes of each complete reciprocatory movement. When each strap is alternately operated, only one-half of the massaging elements will be moved although the other half will also have some motion imparted thereto by reason of the resiliency of ring 8. The massaging movements are radial toward and away from a given area rather than in a simple straight line motion, thereby producing the most desirable massaging action.

The arrangement of the rings 18 and 19 is so related to the rubber ring 8 that it will move the massaging elements outwardly when no pressure is applied to the massaging device between it and the operator's body. When these straps have force applied to them simultaneously away from the massaging device, all the elements will be moved toward the center thereof, and when the massaging device is applied to the body and the applied force is also toward the body, massaging action will take place. If the straps 16 and 17 are tensioned alternately, only one-half of the massaging elements will be effective. Since body pressure must be relieved for permitting the ring 8 to restore the massaging elements to their outward position, it follows that the massaging device must be suitably tilted during alternate tensioning of the straps for permitting ring 8 to perform its function.

During alternate strap operation, there will always be a slight motion of the elements operated by the straps nominally held at rest because of the operator's inability to hold it steady. The ring 8 bears against shoes 9 and, regardless of which strap is tensioned, it will always move one-half of the shoes outwardly whenever pressure between the operator's body and the device is relieved. The straps will always move the massaging elements toward the center of the device and, therefore, there will always be a deformation of the rubber ring 8, thus causing it to restore the massaging elements to their starting position when body pressure is relieved.

What I claim is:

1. A massaging device, comprising a casing having a cavity therein; a plate provided with a plurality of radially extending slots and supported in said cavity; a massaging assembly slidably mounted in each slot; means for sliding each of said massaging assemblies toward one another; other means for sliding said massaging assemblies away from each other; and means for holding each assembly in its radially outward position.

2. A massaging device comprising a circular

5
10

casing; a circular plate provided with a plurality of radial slots and supported in said casing; a plurality of massaging assemblies; a shoe slidably mounted in each slot; means for securing one of said massaging assemblies to each shoe; means operable on said shoe for radially sliding said assemblies toward one another; other means operable on each shoe for radially sliding said assemblies away from one another; and means for holding each assembly in its radially outward position.

3. A massaging device comprising a casing; a plate provided with a plurality of radial slots and supported in said casing; a shoe slidably mounted in each slot; a massaging assembly for each shoe; means connected between each shoe and each massaging assembly for securing the massaging assembly to each of said shoes; a pair of rings circumscribing and acting on one end of each of said shoes; means secured to said rings for sliding said rings relative to each other for moving said shoes in said plate and thereby sliding said massaging assemblies toward one another; and a resilient ring acting on the other end of each of said shoes for sliding said shoes and said massaging assemblies away from one another.

4. A massaging device comprising a circular casing; a circular plate provided with a plurality of radial slots and supported in said casing; a shoe radially mounted in each slot in said plate; a massaging assembly for each shoe; means connected between each shoe and each massaging assembly for pivotally connecting the massaging assembly to each of said shoes; a pair of rings in said casing circumscribing said shoes and in engagement with one end thereof; means operable on said rings for sliding said shoes and massaging assemblies in one direction in said slots; and a resilient ring operable on the other end of said shoes for radially slidably moving said shoes and massaging assemblies in the opposite direction.
